PAPER-FEEDING MECHANISM.

1,076,689.

Specification of Letters Patent. Patented Dec. 17, 1912.

Original application filed January 7, 1909, Serial No. 471,138. Divided and this application filed January 31, 1910. Serial No. 540,964.

To all whom it may concern:

Be it known that we, FREDERICK GEORGE NIND, a subject of the King of Great Britain and Ireland, and FREDERICK JULYAN, a citizen of the United States, residing at Cleveland, in the county of Cuyahoga and State of Ohio, have invented a certain new and useful Improvement in Paper-Feeding Mechanism, of which the following is a full, 10 clear, and exact description, reference being had to the accompanying drawings.

The object of this invention is to provide an efficient means for feeding paper, enabling sheets to be successively dislodged 15 from a block of paper.

The invention relates, particularly, to the means by which such feeding mechanism may be easily and quickly adjusted to receive and hold blocks of paper of varying 20 size, varying thickness, stiffness and weight of the sheets and varying amounts of moisture carried thereby; and to present such paper in such a way as will enable successive sheets to be conveniently dislodged and acted 25 upon.

Our invention is particularly well adapted for use in connection with a folding mechanism.

The present application is a division of 30 our application No. 471,138, wherein a complete folding machine having the present feeding mechanism is shown and described.

In accordance with the above, our invention may be most conveniently summarized 3 as consisting of the combinations of co-operating elements hereinafter more fully explained and set out in the claims.

In the drawings, Figure 1 is a side elevation of our feeding mechanism; Fig. 2 is an 40 enlarged detail, being a perspective view of the means employed to permit the follower plate to be adjusted on its pivots; Fig. 3 is a detail, being a vertical section through the lower end of the means which support the 45 swivel rod of the follower plate; Fig. 4 is an end view of the machine showing, more particularly, the follower plate and the devices employed for adjustably securing it in position; Fig. 5 is an enlarged detail, 50 being a sectional side elevation of the follower plate, the dislodging roll and the means for swinging it, the section planes of the shafts 31 and 32 being in front of the plane through the follower and the section

plane of the shaft 45 being in front of the 55 plane on which the shafts 31 and 32 are cut.

Referring to the several figures of the drawings, in which corresponding parts are indicated by like reference characters:—20 indicates the supporting standards, a pair 60 of such being provided at each side of the machine and each pair having at their upper ends one of the longitudinally-extending side-bars of the frame of the machine, such side-bars being indicated by 21. Each of 65 these side-bars is provided with upwardly-extending lugs 22 in which are secured bars 23 upon which is slidably mounted a frame 24, to which frame is adjustably secured in the manner hereinafter specifically described, a follower plate 25, said follower-plate consisting as shown of a depending 70 vertical portion and a rearwardly-inclined upper portion. The follower-plate is adapted to press against a pile of sheets of 75 paper so as to hold said pile in position to be engaged by suitable mechanism, as, for example, the set of folding rolls shown which are adapted to dislodge the foremost sheet and impart an initial fold thereto. This 80 follower-plate is held against the sheets with the required degree of pressure by a pair of coiled springs 26 secured at their forward ends to the fixed frame of the machine and at their other or rear ends to a cross-bar 27 85 that is adjustably held in any one of a series of notches in the side-bars of the sliding frame 24, as clearly shown in Fig. 1.

The side-bars 21 of the supporting frame are connected near their forward ends by a 90 cross-bar 28. At opposite sides of the supporting frame, are projecting brackets 29 to which may be secured a framework carrying 95 mechanism (not shown) for imparting additional folds to the sheets or other operations desired. The primary folding and dislodging mechanism shown will be described after we have described the devices for permitting the varying adjustments of the feeding mechanism.

In apparatus of this character, it has been found that it is essential to provide means for adjusting the follower-plate in various ways so as to perfectly accommodate it to different kinds of paper and to varying atmospheric conditions, which, as is well known, will affect a pile of sheets in various ways. It is necessary in some instances to

provide that one edge of the follower-plate 1 be slightly closer than the other to the folding rolls, or other corresponding mechanism; it is necessary at times to have either the lower portion or the upper portion of 5 the vertical part of the follower-plate moved in farther than the other portion; and it is also desirable that the follower-plate be adjustable vertically up and down as a 10 whole,—all of these adjustments being provided for in our machine.

The cross-bar portion of the sliding frame 24 (see Fig. 4) is provided with two downwardly-extending ears 57 and 58, the ear 15 57, in the construction shown, being much shorter than the ear 58. These ears are each placed a short distance from the center of the cross-bar of the sliding frame 24. Between these two ears 57—58 fits an arm 20 59 having a horizontal head portion 60 at its upper end that substantially fills the space between the two ears 57—58 and this device is pivotally suspended on a pin 61 that passes through it and through said ears. 25 From the head portion 60 at one side depends a piece 62 that lies close to the inner face of the long ear 58, which piece 62 is enlarged at its 30 upper end and provided with a slot 63 through which a headed bolt 64 passes, the bolt also projecting through the long ear 58 and being adapted to have screwed upon it a thumb-nut 65. By this construction it is evident that the arm 59 can be swung as desired upon its pivot pin 35 61 and held in any desired position by turning up the thumb-nut 65.

66 indicates a heavy rod suitably secured to the under face of the inclined portion of the follower-plate 25. This rod passes 40 through and fits snugly in two eyes 67 and 68 that are formed with an arm 69 that lies over the arm 59. The arm 69 is pivotally connected at its lower end to the lower end of the arm 59, the pivot being indicated by 45 66^a, and at its upper end behind the upper eye 67 it is provided with two ears 70 that lie against the head portion 60 of the arm 59, said ears being provided with short slots 71 through which pass set screws 72 that 50 enter suitable screw-threaded holes in said head portion 60. This construction obviously permits, when the said set screws 72 are loosened, a slight lateral adjustment of the arm 69 so as to move the rod 66 and the 55 follower-plate carried thereby toward one side or the other of the machine, in which adjusted position it can be set by the turning of said set screws 72.

The rod 66 is provided with a collar 73 60 that is adjustably secured to it, preferably by means of a set screw, as shown in Fig. 2, and upon the location of this collar on the said rod depends the extent to which the rod can move downward in its said eyes 65 67—68.

74 indicates two screws that pass through holes in the cross-bar portion of the sliding frame 24, each of said screws being located as shown in Fig. 4 about midway between one side bar of said frame and the center of 70 the cross-bar portion thereof. These screws are adapted to be pressed against the face of the vertical portion of the follower-plate and by screwing up one screw a little more than the other the follower-plate can be 75 turned slightly on its rod 66 as an axis so as to press more tightly toward the folding rolls 30—31 at one side than at the other.

By the construction described, it will be seen that the follower-plate can be raised or 80 lowered, as desired, and held in its adjusted vertical position by securing the collar 73 to the rod 66; that the follower-plate can be swung slightly on the horizontal pivot pin 61 and can be secured after being 85 swung to the desired position by means of the thumb-nut 65; that it can be given a slight side swing on the pivot 66 and secured after being so swung by setting the screws 72; and that one side of the vertical 90 portion of the follower-plate can be advanced slightly closer to the folding rolls 30—31 than the other by proper adjustment of the screws 74,—all of which adjustments permit an almost universal movement of the 95 follower-plate to adapt it to all kinds and conditions of sheets and climatic changes which affect the free movement of said sheets.

75 indicates two vertical rackbars secured 100 in any suitable manner to the rear face of the cross-bar 28 of the supporting frame, and 76 indicates another bar but without the teeth of the bar 75, said bar 76 being also secured to said cross-bar 28 and being located between the two rack-bars 75. The upper ends of these bars extend almost to the plain metal roll 31. These three bars serve to hold the pile of sheets in a vertical position when pressed against them 105 by the vertical portion of the follower-plate 25.

The two rack-bars serve also as means for 110 adjustably supporting devices upon which rest the lower edges of the pile of sheets. 115 As shown (see Fig. 5) these paper-supporting devices consist of two arms 77, one for each rack-bar 75, each arm having at its inner end a head 78 that embraces one of the rack-bars and having near its other end a lug 79. Through the lug 79 and the head 78 passes a rotatable operating rod 80 that carries at one end a pinion 81 suitably affixed to said rod and adapted to mesh with the rack bar. This rod is provided at its 120 outer end with a wheel or handle 82 by the turning of which the rod 80 is rotated, and, through the engagement of the pinion 81 with its rack-bar, the rod and its attached supporting arm 77 are moved up or down on 125 130

the said rack-bar. When the desired position has been reached, the device is clamped in that position by means of a small set screw 83 that passes through a horizontal 5 lip 84 and bears against the hub of the wheel or handle 82.

As shown in Fig. 4, the vertical portion of the follower plate 25 straddles the supporting arms 77 by reason of two vertical 10 openings or slots in the follower plate. These openings conveniently extend from the bottom edge of the follower plate. It results from these openings in the follower plate and from the length of the arms 77 15 that these members intersect each other for various positions of the arms and the follower plate. Accordingly, there is a wide latitude in the amount of paper which may be on the supports, while by these adjustable supports, the pile of paper can be held 20 in proper position so that the central portion of each sheet, or that portion across the sheet to which it is desired to impart the primary fold, will be properly presented to 25 the said folding rolls 30-31.

Referring now to the dislodging and primarily folding mechanism shown herein, the roll 31 is preferably a smooth surface, while the roll 30 is made of yielding material. At 30 one end the shaft 33 of the smooth roll 31 is extended and has secured thereon a suitable driving pulley 34 and at its other end it has a pinion 35. 36 indicates a rocking frame consisting of a bar extending parallel 35 with the smooth roll 31 and pivotally hung from the shaft of such roll by blocks 37 (see Fig. 5) formed with such bar. 38 indicates bearings for the shaft 32 of the yielding roll 30, which bearings have 40 pending lugs 39 that fit in suitable openings in the said blocks 37 and are held there by set screws 40. By this means of supporting the shafts 32, the roll can be slightly adjusted closer to or farther from the smooth 45 roll 31, as required, and secured in the proper adjusted position by the said set screws 40. This construction also admits of the ready detachment of the shaft 32 to permit the changing about or the renewal 50 of the sections of the roll 30, as may be required.

41 indicates a gear rotatable upon a short stub-shaft 42 projecting out from one side of the main supporting frame, said gear being in mesh with the pinion 35 on the shaft 33. On the same stub-shaft 42 and secured to the face of the gear 41 is a pinion 43 which meshes with a large gear 44 rotatably mounted upon a stub-shaft 45. This gear 44 has attached to its outer face so that it will move with such gear a cam 46 (see Fig. 5) upon the surface of which cam rests an arm 47 that projects into a hollow block 48 and is adjustably secured in any desired 65 position by means of a set screw 49. This

hollow block depends from and is secured, by a set screw 50 or otherwise, to a short rock-shaft 51 journaled in one of the side-bars 21 of the supporting frame. To the inner end of this short rock-shaft 51 is suitably affixed a swinging arm 52 having at its lower end a screw-threaded head 53 through which passes a screw-threaded rod 54 that bears against a short swinging plate 55 pivotally attached at its upper end to said swinging arm 52. This plate 55 bears against a rigid downwardly-extending arm 56 that is secured at its upper end to a projecting portion of the frame 36 that is journaled on the shaft 33 and supports the shaft of the yielding roll 30.

From the construction described, it will be seen that as the shaft of the roll 31 is rotated, when power is applied to it through the pulley 34, the gearing described will cause a rotation of the cam 46 on the stub-shaft 45 and such cam will, through the arm 47, cause a turning of the rock-shaft 51, and, as this takes place, the arm 52 will be moved and forced forward the arm 56, causing the frame 36 to turn on its pivotal support and bring the yielding roll 30 more directly over the plain smooth roll 31 so that such yielding roll will be in the position indicated by dotted lines in Fig. 5 and will engage the outermost sheet of the pile of sheets to be folded, causing such sheet to buckle and pass between the two rolls 30-31, said former roll being constantly driven of course by the engagement of its gear with the pinion 35 on the positively driven shaft 33. The extent to which the yielding roll 30 will be moved toward the pile of sheets will be governed by the adjustment of the screw 54. The provision of the swinging plate 55 with which such screw engages serves to take up wear and to apply the pressure better than if the screw impinged directly against the rigid arm 56.

Having thus described our invention, what we claim is:

1. A paper folding device having a roll, means for rotating it, means for supporting a sheet of paper on edge opposite the roll, a follower plate adapted to bear against the rear of the pile of sheets, means for feeding the plate forwardly, and means for enabling adjustments of the plate about two axes at right angles to each other.

2. In a paper feeding device, the combination, with means for supporting a block of paper on edge, of a follower plate for said block of paper, a device to which said plate is swiveled on an axis transverse to said edge, and means for feeding said device toward the paper.

3. In a paper feeding device, the combination, with means adapted to act on the paper, of a follower plate, a member to which said follower plate is swiveled, said

member being hinged on an axis parallel with said means, and means for pressing both the follower plate and the member to which it is swiveled toward said means.

5. A paper feeding device having a roll, a follower plate adapted to press a block of paper toward the roll, a movable member arranged to be locked in various adjusted positions, and a rod carried by the follower plate and swiveled in said movable member.

10. 5. In a paper folding machine, the combination, with a pair of folding rolls and means for rotating them, of means for supporting a pile of sheets on edge opposite said rolls, a follower plate adapted to bear against the rear of the pile of sheets, a member to which said plate is swiveled on an axis at right angles to said rolls, and means for moving said member and plate bodily 20 toward the rolls.

25. 6. In a paper folding machine, the combination, with a pair of folding rolls and means for rotating them, of means for supporting a pile of sheets on edge opposite said rolls, a follower plate adapted to bear against the rear of the pile of sheets, a supporting device in which the follower plate is swiveled and which is movable toward and from the pile of sheets, and means for 30 vertically adjusting the follower plate in said supporting device without interfering with its swivel action.

35. 7. In a paper folding machine, the combination with a pair of folding rolls and means for rotating them, of means for supporting a pile of sheets on edge opposite said rolls, a follower-plate adapted to bear against the rear of the pile of sheets, a supporting device movable toward and from the 40 pile of sheets, a rod secured to the rear face of the follower plate, and means for adjustably securing said rod to said supporting device.

45. 8. In a paper folding machine, the combination with a pair of folding rolls and means for rotating them, of means for supporting a pile of sheets on edge opposite said rolls, a follower plate adapted to bear against the rear of the pile of sheets, a supporting device movable toward and from the 50 pile of sheets, a horizontally-pivoted arm depending from said supporting device, means for locking said arm in any desired position, a rod secured to the rear face of the follower plate, and means for connecting it to said arm.

55. 9. In a paper folding machine, the combination with a pair of folding rolls and means for rotating them, of means for supporting a pile of sheets on edge opposite said rolls, a follower plate adapted to bear against the rear of the pile of sheets, a supporting device movable toward and from the 60 pile of sheets, a horizontally-pivoted arm depending from said supporting device,

means for locking said arm in any desired position, a rod secured to the rear face of the follower plate and means for connecting it to said arm, said rod being vertically adjustable in said connecting means.

70. 10. In a paper folding machine, the combination with a pair of folding rolls and means for rotating them, of means for supporting a pile of sheets on edge opposite said rolls, a follower plate adapted to bear against the rear of the pile of sheets, a supporting device movable toward and from the pile of sheets, a horizontally-pivoted arm depending from said supporting device, means for locking said arm in any desired position, a second arm supported by said first-named arm, means for laterally adjusting said second arm, and a rod attached to said follower plate and supported by said second arm.

75. 11. In a paper folding machine, the combination with a pair of folding rolls and means for rotating them, of means for supporting a pile of sheets on edge opposite said rolls, a follower plate adapted to bear against the rear of the pile of sheets, a supporting device movable toward and from the pile of sheets, a horizontally-pivoted arm depending from said supporting device, means for locking said arm in any desired 80 position, a second arm pivoted to said first-named arm so as to have a lateral swing, means for holding said two arms locked together, and a rod attached to said follower plate and supported by said second arm.

85. 12. In a paper folding machine, the combination with a pair of folding rolls and means for rotating them, of means for supporting a pile of sheets on edge opposite said rolls, a follower plate adapted to bear 90 against the rear of the pile of sheets, a supporting device for said follower plate movable toward and from the pile of sheets, said supporting device comprising a cross-bar portion located in rear of said follower plate, a rod secured to the rear face of said follower plate and connected with said supporting device so as to be axially rotatable, and means for limiting the amount 95 of axial rotation of said rod.

100. 13. In a paper folding machine, the combination with a pair of folding rolls and means for rotating them, of means for supporting a pile of sheets on edge opposite said rolls, a follower plate adapted to bear 110 against the rear of the pile of sheets, a supporting device for said follower plate movable toward and from the pile of sheets, said supporting device comprising a cross-bar portion located in rear of said follower plate, a rod secured to the rear face of said follower plate and connected with said supporting device so as to be axially rotatable, and screws engaging said cross-bar portion 115 of the supporting device and the said fol-

- lower plate to limit the amount of axial rotation of said rod.
14. A paper feeding device having a pair of stationary rack bars, a pair of individual supports for sheets slidably guided up and down independently, a rotatable rod journaled in each support, a gearing between the rod and bar whereby the paper is independently supported at two points.
- 10 15. A feeding device having a vertical rack bar secured to the frame in position to have its side face constitute a paper guide, a horizontal supporting bar vertically guided on said rack bar, a rotatable rod journaled in said supporting bar, a pinion carried by said rod and engaging the teeth of the rack bar, means adapted to clamp the rod to the supporting bar, and a follower plate having a vertical portion parallel with the guiding face of the rack bar, said portion having an opening adapted to straddle the supporting bar, and means for pressing the follower plate toward the rack bar.
16. In a paper folding machine, the combination, with a supporting frame, of a pair of folding rolls, a vertical rack bar secured to the frame beneath said rolls, a support for the sheets to be folded slidably attached to said rack bar, a rotatable rod journaled in said support, a pinion carried by said rod adapted to engage the teeth of said rack bar, means for locking said rod against rotation, and a follower plate having an opening through which the support extends.
- 35 17. In a paper folding machine, the combination with a supporting frame, of a pair of folding rolls, a pair of vertical rack bars secured to the frame beneath said rolls, a pair of supports for the sheets to be folded 40 slidably attached to said rack bars respectively, a rotatable rod journaled in each support, a pinion carried by said rod adapted to engage the teeth of said rack bar, and a set screw carried by said support and adapted to be forced against and hold said rod, whereby the paper may be not only raised and lowered but also tipped in either direction.
18. In a device of the character described, the combination, with a support for a block of paper on edge, of a follower plate, means for moving it bodily toward the block of paper, a hinged support for the follower plate moved by said means, the follower plate being swiveled on said support. 50
19. In a device of the character described, the combination, with means for supporting a block of paper, of a follower-plate mounted to be swung on two axes at right angles to each other and both parallel with a face 60 of the follower plate.
20. In a device of the character described, the combination with means for supporting a block of paper, of a carriage spring-pressed toward the block, and a follower-plate mounted on the carriage and adjustable on axes at right angles to each other. 65
21. The combination in a paper feeding device of a vertical stationary rack bar having teeth along one edge and having a face 70 transverse of the toothed edge constituting a paper guide, of a support for the paper slidable on the rack bar, a rod extending lengthwise of the support and journaled thereon beneath it, a knob at one end of said 75 rod for rotating it, a pinion at the other end of the rod engaging the rack teeth, and a follower plate having an opening straddling the support and rod, the portions of the follower plate on opposite sides of the opening 80 being adapted to stand parallel with the face of the rack bar and held between the follower plate and rack bar, a block of paper resting on edge on the support.
- In testimony whereof, we hereunto affix 85 our signatures in the presence of two witnesses.
